UNITED STATES PATENT OFFICE.

CAMDEN EUGENE KNOWLES AND LEROY DANIEL CORNELIUS, OF PITTSBURG, KANSAS.

SYSTEM FOR FIRING EXPLOSIVES IN MINES.

1,212,072.

Specification of Letters Patent.

Patented Jan. 9, 1917.

Application filed December 7, 1914, Serial No. 875,902. Renewed June 9, 1916. Serial No. 102,794.

To all whom it may concern:

Be it known that we, CAMDEN EUGENE KNOWLES and LEROY DANIEL CORNELIUS, citizens of the United States, residing at 5 Pittsburg, in the county of Crawford, State of Kansas, have invented a new and useful System for Firing Explosives in Mines, of which the following is a specification.

The present invention appertains to a 10 system for firing explosives in mines, and aims to provide a novel and improved system or apparatus adapted particularly for use in coal mines, whereby the explosives in the mine may be conveniently and effectively fired.

As a more specific object, this invention aims to provide a system of such a character 20 that the agencies of air or other fluid under pressure may be utilized for operating circuit closers, to thereby establish electrical circuits within the various portions of the mine to bring the electrical squibs into action for firing the explosives.

Another object of the invention is to provide 25 means in the system, whereby the various sets of circuit closers may be brought into action in a prearranged or predetermined order, so that the explosive in the various portions or branches of the mine 30 may be set off in a given order.

It is also within the scope of the invention, to provide a system of the nature indicated, which will be comparatively simple and non-encumbering in construction, which 35 will be economical in application and maintenance, which will be safe, and which will possess dependability or reliability of action.

With the foregoing and other objects in 40 view which will appear as the description proceeds, the invention resides in the combination and arrangement of parts and in the details of construction hereinafter described and claimed, it being understood that 45 changes in the precise embodiment of the invention herein disclosed can be made within the scope of what is claimed without departing from the spirit of the invention.

The invention is illustrated in its preferred 50 embodiment in the accompanying drawing, wherein:—

Figure 1 is a diagrammatical illustration of the improved system. Fig. 2 is an enlarged sectional view taken through one of 55 the circuit closers and attendant or accompanying parts. Fig. 3 is an enlarged sec-

tional view through one of the pressure valves.

In carrying out the invention there is provided a main air or fluid conduit or pipe 1 extending into the mine, and having one end leading to and connected with an air or fluid tank 2 preferably disposed exteriorly of the mine at a suitable outlying point. A plurality of branches or laterals 60 3 are connected to and extend from the main conduit or pipe 1, and the branches or lateral pipes 3 extend into the various branches or portions of the mine. The main conduit or pipe 1 is preferably provided 65 with a controlling valve 4 adjacent the tank 2, and with an exhaust or outlet valve 5 beyond the valve 4, the valve 4 being operable to control the flow of air or pressure fluid from the tank 2 into the conduit or pipe 1, the valve 5 being operable to permit 70 the compressed air or pressure fluid to discharge from the conduit or pipe 1 to the atmosphere.

Each of the branches 3 of the main conduit 80 or pipe 1, is provided with or has interposed therein a valve structure or mechanism 6 embodying a suitable casing 7 attached to the sections of the branch 3, and having a partition 8 therein provided with openings 85 9 and 10 surrounded by oppositely facing valve seats 11 and 12, respectively. A valve 13 is operable with the seat 11 and is arranged to seat against the pressure of the air or fluid within the conduit or pipe 1, or 90 in other words, the valve 13 is seatable by a movement toward the conduit or pipe 1, considering the direction of flow of air or fluid from the conduit 1 into and through the branches. The valve 13 is provided with 95 a tubular extension or socket 14, and a plug or cap 15 is secured through the casing 7 and is provided with a stem or finger 16 upon which the tubular extension or socket 14 of the valve 13 is slidably snugly to guide 100 the valve 13 to and from the seat 11. A coiled wire expansion spring 17 of graduated tension is positioned within the extension 14 of the valve 13 between the valve and stem or finger 16 and serves to yieldably 105 seat the valve 13 under normal conditions. Each of the valve structures 6 also includes a valve 18 seatable against the valve seat 12 within the casing 7, the valve 18 being seatable in the direction opposite to the direction in which the valve 13 is seatable. The valve 18 is provided with a stem or shank 110

19 received snugly and slidably by a tubular extension 20 of a plug or cap 21 engaged through the valve casing 7, so that the valve 18 is guided for movement to and from the 5 seat 12.

Each of the branches 3 is equipped with a set or series of upstanding nozzles 22, which carry and operate the circuit closers 23. Each of the circuit closers comprises an 10 apertured graphite piston 24 secured upon the upper end of the respective nozzle 22, and a cylinder 25 mounted slidably upon the piston 24, the lower end of the cylinder 25 being open, and the upper or outer end 15 thereof being closed, and being provided with a socket 26 receiving a block of insulation 27. A switch member 28 in the form of a cap, is engaged over the block of insulation 27, so as to be insulated from the cylinder 20 25.

Each of the circuit closers 23 is preferably inclosed within a case or box 29 having the nozzle 22 engaged upwardly through its bottom.

25 An electrical circuit is associated with and arranged to be operated by each of the circuit closers 23, the various electrical circuits being distributed throughout the extent of the mine, or the selected portions thereof. 30 Each of the electrical circuits embodies a pair of conductors 30 which are bridged by electrical squibs 31. The conductors 30 extend to the case or box 29 and their respective ends are connected to binding posts 32 35 engaged to the bottom of the box or case 29, and suitable batteries 33 are disposed within the case or box 29 for establishing the electrical circuit at the opportune time, although it is to be understood that an electrical circuit 40 may be established by a dynamo or other suitable source of electrical current.

In order that the circuit closer 23 may close the circuit through the conductors 30, an insulated shelf or block 34 is secured 45 within the case 29 above the circuit closer 23, and a pair of binding posts 35 are engaged through the shelf or block 34, and have contact brushes or springs 36 secured to their lower ends and lying in the path of the 50 switch member 28, so that when the cylinder 25 is raised or pushed away from the nozzle 22, the switch member 28 in contacting with the free ends of the brushes or springs 36 will close the circuit. The end of one conductor 30 is connected to one of the brushes or contacts 36 by means of a leader or conductor 37, and the end of the other conductor 30 is connected to one terminal of the batteries 33, by a wire or conductor 38, and the other terminal of the batteries 33 is connected to the other brush or contact 36 by a wire or conductor 39.

It is preferable to provide a manually operable switch 40 in one of each pair of conductors 30 adjacent the case or box 29, in

order that the electrical circuit may be opened and left opened during such periods when the establishment of the electrical circuit through the conductors 30 is not desired.

The branches or lateral pipes 3 are preferably grounded at intervals, as at 41, to eliminate stray or foreign circuit through the metallic conduits or pipes, and to thereby avoid any cross circuits or the like, which would be liable to prematurely or accidentally bring the squibs into action. The conductors of the electrical circuits are also insulated thoroughly to enhance the safety of the present system. 70 75

A coal mine may be readily and economically equipped with the present apparatus, the conduits or pipes 1 and 3 being readily and inexpensively applied therein, and it being noted that the electrical circuits are of short length of extent, and are isolated from their neighboring circuits, so as not to interfere with one another. In this manner, the use of trunk lines from the various firing circuits to an outlying generating station are eliminated, as has heretofore been the cause 80 85

of a considerable outlay in equipping mines with the all electric systems, and such systems have not only been expensive to install and maintain, but have also been subjected to the dangers of sneak circuits shunts, cross circuits and the like, rendering the systems unreliable. The springs 17 of the various pressure valves 13 are of graduated tension, so that they will possess different degrees of strength, and in this manner the valve 13 having the weakest spring will be opened first under the pressure of air or fluid within the conduit or pipe 1, and the respective valves 13 will be opened in sequence or regular order according to the arrangement of 90 95 100 105 the springs 17.

When it is desired to fire the explosives within the mine, the compressed air or pressure fluid within the tank 2 is admitted into the main conduit or pipe 1 by opening the 110 valve 4, and as the pressure rises within the pipe 1, the valves 13 of the respective branches 3 will be opened in succession, and as soon as each of the valves 13 is forced open due to the fact that the compressed air overcomes the tension of the respective springs 17, the air will rush into the respective branches 3 and nozzles 22 thereof, so as to raise the pistons 25 and cause the switch members 28 carried thereby to close the respective electrical circuits, and whereupon the electrical squibs 31 will be set off for firing the explosives in the immediate vicinity of the mine. Thus, as the pressure of the air or fluid within the pipe or conduit 1 115 120 125 rises, the various sets or series of circuit closers will be operated in a regular or given order, and according to the time required to raise the pressure within the pipe or conduit 1. 130

After all of the shots have been fired, the operator or attendant opens the main conduit or pipe 1 to the atmosphere, by opening the valve 5, which will enable air and 5 gases from the pneumatic system to be discharged into the atmosphere, the valves 18 which are ordinarily seated by the compressed air, being opened by the backward flow of the air or gas to permit the gas to 10 flow from the branches 3 into the conduit or pipe 1 and thence into the atmosphere by way of the valve 5.

So soon as the air or fluid is exhausted sufficiently from the piping, all of the cylinders 25 of the circuit closers will descend by gravity and release all of the switch members 28 from the contacts 36, to thereby open all of the circuits. As a means for further precaution against accidents, the switches 40 20 at the heads of the firing circuits, may be opened at such times when it is not desirable for an electrical current to be set up in the circuits.

The present system in embodying the 25 pneumatic apparatus for operating the circuit closers, eliminates the use of expensive electrical trunks, and furthermore enables the various circuits to be readily and timely closed.

30 The present system is operated when all of the miners are out of the mine, and there is no danger or risk incurred to life and limb. The shot firer may readily operate the system without subjecting himself to 35 injury, and the present system is of advantage for other reasons which will be apparent to those versed in the art.

What is claimed is:—

1. A system for firing explosives in mines, 40 comprising a fluid conduit extending into the mine, a normally open electrical circuit in the mine and including an electrical squib, and a fluid operated circuit closer for the said circuit and operatively connected 45 to the said conduit.

2. In a system for firing explosives in mines, a fluid conduit extending into the mine, a plurality of fluid operated circuit closers operatively connected thereto, a normally open electrical circuit in the mine 50 co-operable with each circuit closer and arranged to be closed thereby, said circuits including electrical squibs and means for

rendering the various circuit closers inoperative until various predetermined pressures 55 of the fluid are attained.

3. A system for firing explosives in mines, comprising a fluid conduit extending into the mine and having a plurality of branches extending into the branches of the mine, 60 each branch having a valve for controlling the passage of fluid from the conduit thereto, means for holding the respective valves closed until the pressure of the fluid within the conduit rises to predetermined degrees, a 65 fluid operated circuit closer operatively connected to each branch, and a normally open electrical circuit associated with each circuit closer and arranged to be closed thereby, said circuits including electrical squibs. 70

4. A system for firing explosives in a mine, comprising a fluid conduit extending into the mine and having a plurality of branches extending into the branches of the mine, each branch having a valve for controlling the passage from the conduit thereto and a check valve for allowing the fluid to flow back from the branch into the conduit, means for holding the respective first mentioned valves closed until the pressure 80 of the fluid within the conduit rises to predetermined degrees, a fluid operated circuit closer operatively connected to each branch, and a normally open electrical circuit associated with each circuit closer and arranged 85 to be closed thereby, said circuits including electrical squibs.

5. A system for firing explosives in a mine, comprising a fluid conduit extending into the mine and having a nozzle, a cylinder 90 slidable upon said nozzle to be moved thereon by the action of the fluid in the conduit, an electrical circuit in the mine including an electrical squib and a pair of contacts, and an insulated switch member carried by said cylinder and co-operable with 95 said contacts to close said circuit when the cylinder is moved by the action of the fluid.

In testimony that we claim the foregoing as our own, we have hereto affixed our signatures in the presence of two witnesses. 100
